UNITED STATES PATENT OFFICE.

BENJAMAN F. BARNES, OF ROCKFORD, ILLINOIS.

DRILLING-MACHINE.

No. 831,697.

Specification of Letters Patent.

Patented Sept. 25, 1906.

Application filed September 30, 1901. Serial No. 77,102.

To all whom it may concern:

Be it known that I, BENJAMAN F. BARNES, a citizen of the United States, residing at Rockford, in the county of Winnebago and State of Illinois, have invented certain new and useful Improvements in Drilling-Machines, of which the following is a specification.

One of the objects of this invention is the production of a drilling-machine having a quick-advance and quick-return feed movement of the drill-spindle.

The invention further refers to a means for varying the extent of such quick-advance movement with relation to the slower work-feed movement of the spindle.

The invention further refers to a means for yieldingly connecting either the quick feed or the work-feed to the spindle in order to guard against breakage when the quick feed is thrown into action.

The invention further refers to a driving means for the quick feed capable of slipping to prevent breakage.

A further object of the invention is the embodiment in a drilling-machine of the various improvements more fully hereinafter specified.

In the accompanying drawings, Figure 1 is a perspective view of a drilling-machine embodying the features of my invention, showing the drill-spindle partially lowered by a full movement of the quick feed. Fig. 2 is a view similar to the preceding one taken from the opposite side of the machine, but showing the drill-spindle in its elevated or initial position. Fig. 3 is a detail perspective view illustrating a part of the quick-feed mechanism, showing said mechanism in the position assumed after having lowered the drill-spindle to its work, as in Fig. 1. Fig. 4 is a detail perspective view of parts of the mechanism looking upon that side of the drilling-machine shown in Fig. 1. Fig. 5 is a view, partly in section, taken on the axial center of the transverse shaft for feeding the drill-spindle. Fig. 6 is a vertical section on dotted line *a a* of Fig. 5. Fig. 7 is a vertical sectional view illustrating the spring-operated

detent-plunger for holding the shifting mechanism illustrated in Fig. 4 in either of its two positions. Fig. 8 is a side elevation of the toothed sector, the movement of which drives the drill-spindle through its quick advance and return movements. Fig. 9 is a diametric sectional view of the locking-disk,

the releasing of which permits the movement of the quick advance and return feed. Fig. 10 is a face view of said locking-disk. Fig. 11 is a fragmentary vertical central section 60 through the drill-spindle, illustrating its connection with the spindle feed mechanism.

In the embodiment herein shown of my invention I have combined with the usual work-feed of a drilling-machine an automatically-actuated quick advance and return feed for the drill-spindle. The quick feed and the slower work-feed (where said work-feed is power-driven) are operated conjointly during the first part of the downward movement of the drill-spindle, the work-feed being merged in the quick feed; but when the drill reaches its work the quick-feed movement by previous adjustment terminates and from this point on the spindle is advanced under 70 the action of the work-feed alone. As the drill emerges through its work the work-feed is automatically disconnected from the drill-spindle, and said spindle is raised to its initial position by the return action of the quick 75 feed. The relative extent of the quick downward movement of the drill-spindle and of its slower movement under the action of the work-feed, also the position that the drill-spindle assumes as its initial position, are 80 severally placed by means of certain adjustments of the mechanism wholly within the control of the operator.

In the construction of the drilling-machine hereinbefore briefly outlined I provide the 90 usual supporting-column 1, having the horizontal bearings 2, the vertical bearings 4, formed integral with said column, the horizontal shaft 3, lying in said bearings 2, and the vertical drill-spindle 5, supported in the 95 bearings 4, said horizontal shaft and said drill-spindle being rotatably connected by means of the bevel-gears 6. The horizontal shaft is also provided with the cone drive-pulley 7 and with the cone work-feed pulley 8, the 100 former carrying a belt 9, which runs over and communicates motion from a similar cone-pulley upon a counter-shaft (not shown) at the foot of the column 1. Rotatory motion to operate the work-feed is communicated 105 from the cone-pulley 8 on the shaft 3 to the shaft 10, rotatably mounted in suitable bearings in a bracket 11, fixed with relation to the supporting-column 1. The shaft 10 carries at its rear end a cone-pulley 12 and at its 110 forward end a worm 13, a belt 14 running over the cone-pulley 8 and said cone-pulley

12. A vertical shaft 15 is rotatably mounted in the bearings 16 and carries at its upper end a worm-wheel 17, adapted to mesh with the worm 13, fixed to the shaft 10. The 5 lower end of the shaft 15 is provided with a worm 18, fixed thereto, which worm is adapted to mesh with the teeth of a worm-wheel 19, loosely mounted upon the transverse spindle feed-shaft 20. A ratchet-wheel 21 lies beside the worm-wheel 19 and is fixed in any suitable manner to the shaft 20. A pawl 22 is mounted upon the side of the worm-wheel 19 by means of the pivot 22^a, and the point of said pawl is held by the 15 spring 22^b in engagement with the teeth of the ratchet-wheel 21. At its free end the pawl 22 carries a fixed stud 22^c, having an offset cone-shape head, said head projecting beyond the ratchet-wheel 21 in a direction 20 away from the worm-wheel 19. A collar 23, loosely mounted upon a hub 24, integral with and extending from the supporting-column 1, is provided with a conical forward end adapted to engage the conical head of the stud 22^c 25 of the pawl 22 to move said pawl upon its pivot 22^a and raise the tooth of said pawl from engagement with the teeth of the ratchet-wheel 21 when said collar 23 is moved toward said ratchet-wheel 21. Outside the 30 worm-wheel 19 the shaft 20 bears a wheel 25, having recesses 25^a in its periphery to receive a rod for manually moving the drill-spindle.

An oscillatory operating-shaft 26 is mounted in the bearings 27, fixed with relation to the supporting-column 1, and carries two segment-gears 28 and 29. The teeth of the gear-segment 28 mesh with teeth 31, formed upon the upper side of the collar 23, from which it 35 will be seen that a movement of the segment 28 will slide the collar 23 longitudinally of the shaft 20. The teeth of the segment 29 mesh with the corresponding teeth of a vertical rack-bar 32, which rack-bar is slidably 40 mounted at its lower end in a suitable guide-opening in one of the bearings 27 for the shaft 26 and at its upper end in a similar opening in the bearing 33. The upper end of this 45 rack-bar is provided with a notch 32^a, adapted to receive the flange of a locking or escape- 50 ment disk for controlling the movement of the quick-feed mechanism, to be hereinafter more fully described.

At its forward end the operating-shaft 26 55 carries a hand-lever 34, which hand-lever is fixed to the shaft 26 and is within easy reach of and adapted to be grasped by the operator. The shaft 26, near its rear end, carries an arm 35, in the forward end of which arm is rotatably mounted a roller 36, which roller is adapted to contact the tapering forward end of a spring-plunger 37, lying in a pocket 37^a of a portion of the supporting-column 1 and held forward therein by means of a coil-spring 37^b. A pin 37^c limits the forward

movement of the plunger 37. When the shaft 26 is oscillated, the roller 36 passes the point of the plunger 37, depressing said plunger against the action of its spring 37^b. The plunger thus acts as a detent to hold the 70 shaft 26 positively in either one of its two oscillatory positions, also by reason of its spring action serving to move the rack-bar 32 so that its notch 32^a is thrown out of coincidence with the flanges upon the locking-disk 75 hereinbefore mentioned.

A movable clamping-stud 38 is adjustably secured to the feed-rack of the drill-spindle by means of the screw-threaded rod 38^a, which rod passes through the opening between two adjacent teeth of the feed-rack and enters a correspondingly-screw-threaded opening in the stud 38. This adjustable clamping-stud is adapted to engage the arm 30, fixed on the shaft 26, and the position of the stud 38 upon the rack of the drill-spindle 80 thus determines the point at which the collar 23 will be slid upon the hub 24 and the tooth of the pawl 22 withdrawn from the teeth of the ratchet 21. In practice this is 85 necessary when the drill has passed through its work, and the work-feed should be disconnected from the shaft 20 in order that said shaft may be rotated in a contrary direction by the quick feed to return said drill-spindle 95 to its initial position.

The quick advance and return feed for the drill-spindle will next be described.

A shaft 39 is rotatably supported in bearings 40 integral with the supporting-column 100 1, and at its rear end said shaft 39 carries a loose pulley 41, having a finished hub 41^a. At a point adjacent to the pulley 41 the shaft 39 carries a spider 42, fixed to said shaft, and this spider has two friction-blocks 42^a, adapted to bear upon diametrically opposite points in the periphery of the hub 41^a. The frictional contact between these blocks and the hub is regulated and wear taken up by means of the adjusting-screws 42^b. The pulley 41 is continuously rotated during the operation of the drilling-machine by means of a belt 43, running over said pulley from a pulley on the counter-shaft (not shown) at the base of the drill. The friction between the 115 pulley 41 and the shaft 39 thus tends at all times to rotate said shaft and will rotate it save when it is locked against movement by a mechanism to be described later herein. It will be seen that the hub 41^a and spider 42 120 constitute a friction-clutch for transmitting power from the counter-shaft alluded to to the quick-feed mechanism. To the forward end of the shaft 39 is fixed a worm 44, adapted to mesh with the teeth of the worm-wheel 125 46, fixed upon a shaft 45, rotatably mounted in the upper part of the supporting-column 1. The shaft 45 also carries the locking-disk 47, hereinbefore referred to, which disk has two concentric flanges 47^a and 47^b, separated at 130

their ends by the spaces 47^c and 47^d. The notch 32^a in the rack-bar 32 is just sufficient in width to permit the passage of one of the flanges 47^a and 47^b.

5 An oscillatory yoke or connecting-rod 48 is pivotally connected to the face of the worm-wheel 46 by means of the wrist-pin 46^a, which wrist-pin is, in effect, a crank-arm on the shaft 45. A gear-sector 50 is pivotally 10 mounted, by means of the bolt 50^a, to the supporting-column 1, and the teeth of this sector are adapted to mesh with those of a pinion 51, carried by the stud 51^a, and those of the spur-gear 52 (to which gear said pinion is 15 fixed) are adapted to mesh with the teeth of a pinion 53, loosely mounted upon the shaft 20. A hub 54 is fixed to the shaft 20 by means of the nut 54^a and has a rotative connection with the pinion 53 by means of the 20 teeth 55, formed in the meeting faces of said hub and said pinion. This releasable connection between the pinion 53 and the shaft 25 is provided in order that the quick feed may be disconnected and the drill-spindle advanced under the work-feed alone, if desired.

The gear-sector 50 is provided with an elongated opening 56, adapted to receive the block 49, said opening having sufficient 30 length to permit of a complete reciprocation of said block 49 without any corresponding movement of the gear-sector 50. Screws 57 and 58 enter the elongated opening 56 from opposite ends thereof, lying in suitable screw-threaded openings (not shown) extending 35 through the end walls of said opening. The extent of the movement of the gear-sector 50 as imparted by the reciprocation of the block 49 is governed by the positions of the screws 40 57 and 58 with reference to the ends of the elongated opening 56. If only a slight movement of the sector (and consequently of the drill-spindle) is desired, the screw 58 is withdrawn almost entirely from the opening 56; but if a considerable movement of the sector 45 is necessary said screw is projected farther into said opening. During a downward movement of the drill-spindle the block 49 bears upon the upper end of the screw 58, 50 and this screw is intended to be adjusted in position in the elongated opening 56, so that the yoke 48 will have moved to its lowermost position, Fig. 3, when the drill reaches a point adjacent to its work. The position of 55 the screw 57 is such that the gear-sector 50 may be oscillated downward by the work-feed (through the gear connection between the shaft 20 and said sector) until the drill emerges through its work. When the drill 60 reaches this point, the screw 57 may be in contact with the upper side of block 49, or it may be at some distance from said block, depending upon the height to which it is desirable to raise the drill above its work in 65 attaining the initial position of the spindle.

From the foregoing description it will be seen that the screws 57 and 58 may be adjusted so that much or little of the vertical movement of the yoke 48 is transmitted to the drill-spindle 5, according to the necessities of the work and the desires of the operator. It will also be noted that the sector 50 is constantly "in gear" with the shaft 20, so that a sufficient amount of "lost motion" must be provided for to permit the drill-spindle to descend through its work after the yoke 48 has assumed its lowest position. It will also be seen that the work-feed and the quick feed both act conjointly upon the drill-spindle during the rapid lowering of said spindle, during which time the quick feed outstrips the work-feed, causing the ratchet-wheel 21 to slip under the pawl 22, said pawl clicking over the teeth of the ratchet-wheel. When the drill-spindle reaches its work, the quick feed ceases, the work-feed alone then advancing the spindle.

The object in driving the quick-feed mechanism independently of the work-feed or the spindle-rotating means is to permit of 90 always operating the quick feed at maximum speed regardless of variations in the speed of the work-feed or spindle.

In operation, assuming the parts to be in the positions indicated by Figs. 2 and 4 of the drawings or in any other one of its initial positions that may be selected by the operator, the piece to be drilled is placed upon the drill-table and the hand-lever 34 moved by the operator from right to left. This movement 95 of the hand-lever oscillates the shaft 26 and raises the rack-bar 32 so that its notch 32^a coincides with the flange 47^a of the locking-disk 47, releasing the disk (together with the worm-wheel 46 and the shaft 39) to the 100 rotative tendency of the constantly-driven friction-pulley 41, the oscillation of said shaft 26 also rocking the arm 35 into a position in which the spring-plunger 37 exerts a tendency to raise said arm 35 and with it the rack 105 bar 32. The rotation of the shaft 39 drives the worm-wheel 46, depressing the yoke 48 and oscillating the sector-gear 50. This oscillatory movement of the gear 50 drives the train of gears 51, 52, and 53 to quickly lower 110 the drill-spindle 5 and to bring the drill into a position adjacent to the work. At this point the yoke has reached the limit of its downward movement, the locking-disk 47 having made half of a revolution, bringing the notch 115 47^c thereof into coincidence with the rack-bar 32. When this occurs, the rack-bar is instantly raised by the spring-plunger 37 so that its notch 32^a is out of coincidence with the flanges of the locking-disk 47, stopping 120 the rotation of said disk and preventing the operation of the quick feed. The drill-spindle is now advanced by the work-feed, and when the drill emerges through its work the 125 adjustable clamping-stud 38 upon the rack- 130

bar 5^a of the drill-spindle engages the arm 30 of the oscillatory shaft 26, whereupon continuing downward movement of the drill-spindle oscillates the shaft 26, sliding the collar 23 lengthwise of the hub 24 and causing the conical forward end of said collar to engage with the conical head of the stud 22^c, carried by the pawl 22. The engagement of the collar 23 with the stud 22^c moves the free end of the pawl 22 outward upon its pivot 22^a against the tendency of the spring 22^b and withdraws the tooth of said pawl 22 from engagement with the teeth of the ratchet-wheel 21, freeing the shaft 20 from connection with the constantly-rotated worm-wheel 19 of the work-feed.

The oscillatory movement just described of the shaft 26 moved the arm 35 downward into a position where the spring-plunger 37 tends to move said arm still farther downward and also moved downward the rack-bar 32 by reason of the segment-gear (29) connection between said shaft 26 and said rack-bar, which movement of the rack-bar brought the notch 32^a of the rack-bar into coincidence with the flange 47^b of the locking-disk 47, thereby releasing said locking-disk (and the shaft 39 and worm-wheel 44) to the rotative tendency of the constantly-driven pulley 41 and permitting a movement of the quick-feed mechanism to elevate the yoke 48 and sector 51, and thus restore the drill-spindle 5 to its initial position. When the rotation of the locking-disk 47 brings the notch 47^a into coincidence with the rack-bar 32, the spring-plunger 37 draws said rack-bar downward to bring the notch 32^a out of coincidence with the flanges of said disk, stopping the operation of the quick-return feed. The mechanism has now made a complete cycle of its movement and stands at rest, ready for the removal from the drill-table of the work just operated upon and the substitution therefor of a new piece of work. When such new work is placed upon the drill-table, the hand-lever 34 is again moved by the operator, and the cycle of movement just described is repeated.

Some yielding connection between the feed-shaft and either the work-feed or the quick feed is necessary to permit the change from one feed to the other without the breakage of parts which would result from an unyielding connection between both feeds and the drill-spindle. While I have herein shown a pawl-and-ratchet connection for this purpose, it is apparent that a yielding spring connection or various other forms of ratchet-clutches might be provided to accomplish this purpose.

The object in providing a friction-drive for the quick-feed mechanism instead of a positive feed is to prevent breakage should the downward feed movement of the drill-spindle be arrested by some obstacle in its path.

A gear-drive or other positive connection

would cause breakage in the event of such accidental stoppage; but with a friction-drive for the quick-feed mechanism the danger of such breakage is obviated.

It is apparent that the work-feed instead of being power-driven might be operated by hand and the drill-spindle advanced and returned by the quick feed in the same manner as hereinbefore described. It is further obvious that many other changes and modifications might be made in the quick-feed mechanism without departing from the spirit and scope of my invention; also, that the quick-advance movement of the spindle might be eliminated and the quick-return movement retained, in view of all of which I desire to have it understood that I do not limit myself to the embodiment herein shown of my invention, but claim said invention broadly.

The term "slip connection" used herein is intended to include the various mechanical appliances for permitting one feed to actuate the spindle while the other feed is moving at a different rate of speed or is stationary. Such mechanisms include not only pawls and ratchets, friction and toothed clutches, and other friction slipping devices, but also include yielding spring connections arranged to take up motion, and thereby permit a greater rotative movement of one shaft than of the other. Some form of slip connection interposed between one of the feeds and the drill-spindle, or included as an element of one of said feeds, is highly important, if not absolutely necessary, in the successful operation of mechanism embodying certain important features of this invention, wherefore applicant desires not to be limited by the terms chosen to describe said invention.

I claim as my invention—

1. In a drilling-machine, in combination, a drill-spindle; means for advancing said drill-spindle under two different feed-speeds during each advance movement of said spindle; and a slip connection between said spindle and the means for advancing said spindle under the slower feed-speed.

2. In a drilling-machine, in combination, a drill-spindle; means for advancing said drill-spindle under two different feed-speeds during each advance movement of said spindle; means for varying the extent of the advance movement of the spindle under one of said feed-speeds; and a slip connection between said spindle and the means for advancing the spindle under the slower feed-speed.

3. In a drilling-machine, in combination, a drill-spindle; a work-feed mechanism and a quick advance feed mechanism having a driving connection with said spindle, said work-feed mechanism having a slipping connection between certain of its elements.

4. In a drilling-machine, in combination, a drill-spindle; a work-feed for advancing the spindle; a quick feed independent of the

work-feed for advancing the spindle; a yielding connection between said spindle and said work-feed; and means for varying the extent of the advance movement of the spindle under one of said feeds.

5. In a drilling-machine, in combination, a
drill-spindle; means for raising and lowering
the spindle; a work-feed adapted to actuate
said raising and lowering means; a quick
feed, independent of the work-feed, for actuating
said raising and lowering means; a slip
connection between said work-feed and said
raising and lowering means; a driving means
for actuating said quick feed; and adjustable
means for rendering said quick feed ineffect-
ive to operate the raising and lowering means
for a portion of the movement of said quick-
feed driving means.

6. In a drilling-machine, in combination, a
20 drill-spindle; a work-feed for said spindle; a
quick advance and return feed for said spin-
dle independent of the work-feed; a slip con-
nection between said work-feed and said spin-
dle; means tending to actuate said quick
25 feed; means for holding said quick-return
feed from action; and means for releasing
the quick-return feed to action.

7. In a drilling-machine, in combination, a
drill-spindle; a work-feed for said spindle; a
30 quick advance and return feed for said spin-
dle independent of the work-feed; a slip con-
nection between said work-feed and said
spindle; means tending to actuate said quick
feed; means for holding said quick-return feed
35 from action; means for releasing the quick-
return feed to action; and means for adjust-
ably limiting the extent of the efficient ac-
tion of the quick feed to advance the spindle.

8. In a drilling-machine, in combination, a
40 drill-spindle; a work-feed and a quick ad-
vance and return feed for said spindle; a slip
connection between said work-feed and said
spindle; means tending to actuate said quick
feed; a detent for holding said quick feed
15 from action; and means adapted to be actuated
by the work-feed for withdrawing said
detent to release the quick-return feed to
action.

9. In a drilling-machine, in combination, a
50 drill-spindle; a work-feed and a quick ad-
vance and return feed for said spindle; a slip
connection between said work-feed and said
spindle; means tending to actuate said quick
feed; a detent for holding said quick feed
55 from action; and means adapted to be actuated
by the advance movement of the drill-
spindle under the work-feed for withdrawing
said detent to release the quick-return feed
to action.

60 10. In a drilling-machine, in combination, a drill-spindle; a feed-shaft therefor; a spindle-feed mechanism comprising a worm-wheel having a slip connection with said feed-shaft; and a second spindle-feed mechanism
65 operatively connected with said feed-shaft,

65 operatively connected with said feed-shaft,

the said spindle-feed mechanisms being arranged to operate at different speeds.

11. In a drilling-machine, in combination, a drill-spindle; a feed-shaft for said spindle; two gears on said feed-shaft, one of said gears having a ratchet connection with said shaft; a work-feed adapted to engage with said last-mentioned gear; a quick-advance feed adapted to mesh with the other one of said gears; and means for varying the extent of the advance movement of said spindle under the work-feed. 70 75

work feed. 12. In a drilling-machine, in combination, a drill-spindle; a feed-shaft for said spindle; two gears on said feed-shaft, one of said gears having a ratchet connection with said shaft; a work-feed adapted to engage with said last-mentioned gear; a quick-advance feed adapted to mesh with the other one of said gears; and means for varying the extent of the advance movement of said spindle under the quick feed. 80 85

13. In a drilling-machine, in combination, a drill-spindle; a feed-shaft for said spindle; two gears on said feed-shaft, one of said gears having a ratchet connection with said shaft; a work-feed adapted to engage with said ratchet-gear; and a quick-advance feed adapted to mesh with said other gear. 90

14. In a drilling-machine, in combination, 95
a drill-spindle; a feed-shaft for said spindle;
two gears on said feed - shaft, one of said
gears having a ratchet connection with said
shaft; a work-feed adapted to engage with
said ratchet-gear; a quick advance and re- 100
turn feed adapted to mesh with said other
gear; and means for breaking said ratchet
connection during the rotation of said feed-
shaft in one direction.

15. In a drilling-machine, in combination, 105
a drill-spindle; a spindle-feed shaft; a gear
loosely mounted on said shaft; a ratchet-
wheel fixed on said shaft; a pawl pivotally
mounted on said gear and adapted to engage
said ratchet-wheel; means for rotating said 110
gear to rotate the shaft in one direction;
means for rotating said shaft in a contrary
direction; and means for withdrawing said
pawl from engagement with said ratchet-
wheel. 115

16. In a drilling-machine, in combination, a drill-spindle; a spindle-feed shaft; a gear loosely mounted on said shaft; a ratchet-wheel fixed on said shaft; a pawl pivotally mounted on said gear and adapted to engage said ratchet-wheel; a stud on said pawl; a collar loosely mounted on said shaft and adapted to engage said stud to withdraw the pawl from engagement with the ratchet-wheel; means for rotating said gear to rotate the shaft in one direction; means for sliding said collar longitudinally of said shaft; and means for rotating said shaft in a contrary direction.

17. In a drilling-machine, in combination, 130

- a drill-spindle; a work-feed for advancing the spindle; a quick feed driven independently of the work-feed for returning the spindle; a driving means capable of slipping for operating said quick feed; means for holding said quick feed from action against the actuating tendency of said driving means; and means automatically actuated for releasing the quick-return feed to action.
18. In a drilling-machine, in combination, a drill-spindle; a quick advance and return feed for said spindle; a friction driving means for actuating said quick feed; means for holding said quick feed from action against the actuating tendency of said friction-driving means; and means for releasing the quick feed to action.
19. In a drilling-machine, in combination, a drill-spindle; a quick advance and return feed, for said spindle, said quick feed comprising a friction driving means; a detent for holding said quick feed from actuation by said friction driving means; and means for withdrawing said detent.
20. In a drilling-machine, in combination, a drill-spindle; a quick feed, for advancing the spindle, said quick feed comprising a friction driving means and means for withholding said driving means from action to move said spindle; and means for releasing said driving means.
21. In a drilling-machine, in combination, a drill-spindle having a quick feed, said quick feed comprising a friction driving means and means for locking said quick-feed mechanism against the action of said friction driving means; and means adapted to be manually operated for releasing said locking means.
22. In a drilling-machine, in combination, a drill-spindle having a quick feed; said quick feed comprising a friction driving means, an oscillatory lever actuated by said driving means and having a gear connection with said spindle, means for adjustably limiting the extent of movement of said lever, and means for locking said quick-feed mechanism against the action of said friction driving means.
23. In a drilling-machine, in combination, a drill-spindle having a quick feed to advance the spindle, said quick feed comprising a friction driving means, an oscillatory lever having a gear connection with said spindle, means actuated by said driving means for moving said lever, and a detent for said driving means; and means for withdrawing said detent.
24. In a drilling-machine, in combination, a drill-spindle; and means for advancing said spindle comprising a reciprocatory device, an oscillatory lever, and an adjustable lost-motion connection between said device and said lever.
25. In a drilling-machine, in combination, a drill-spindle, said quick feed comprising an oscillatory lever having a gear connection with said spindle, a crank-arm, means for rotating said crank-arm, and an adjustable lost-motion connection between the crank-arm and the lever for moving said lever.
26. In a drilling-machine, in combination, a drill-spindle, and a quick feed for advancing the spindle, said quick feed comprising an oscillatory lever having a gear connection with said spindle, a crank-arm, a connecting-rod extending between said crank-arm and said lever, and means adapted to rotate said crank-arm.
27. In a drilling-machine, in combination, a drill-spindle having a quick feed to advance the spindle, said quick feed comprising an oscillatory lever having a gear connection with said spindle, a crank-arm, a connecting-rod extending between said crank-arm and said lever, means constantly tending to rotate said crank-arm, and means for locking said crank-arm from rotation; and means for releasing said crank-arm to rotation.
28. In a drilling-machine, in combination, a drill-spindle having a quick feed to advance the spindle, said quick feed comprising an oscillatory lever having a gear connection with said spindle, a crank-arm, a yoke pivotally connected with said crank-arm and having an adjustable lost-motion connection with said lever; a shaft for rotating said crank-arm, a constantly-rotated pulley mounted on said shaft and having a frictional engagement therewith, and means for locking said crank-arm from rotation; and means for releasing said crank-arm to rotation.
29. In a drilling-machine, in combination, a drill-spindle having a quick feed to advance the spindle, said quick feed comprising an oscillatory lever having a gear connection with said spindle, a crank-arm, a yoke pivotally mounted on said crank-arm and having a sliding connection with said lever, means for adjustably limiting the extent of movement of said sliding connection, a shaft for rotating said crank-arm, a pulley arranged to be constantly rotated, on said shaft, means for causing said pulley to frictionally engage said shaft to rotate the shaft, and a locking-disk adapted to prevent rotation of the crank-arm; and means for releasing said crank-arm to rotation.
30. In a drilling-machine, in combination, a drill-spindle; a work-feed and a quick advance and return feed for said spindle, said quick feed comprising a reciprocatory device; and means for permitting lost motion between said device and the spindle to adjustably limit the effective movement of said device to operate the quick feed.
31. In a drilling-spindle, in combination, a drill-spindle; a quick advance and return feed for said spindle, said feed comprising a reciprocatory device; and adjustable means

for permitting lost motion between said device and the spindle, to limit the effective movement of said device to operate the quick feed.

5 32. In a drilling-machine, in combination, a drill-spindle; and a quick advance and return feed for said spindle, said quick feed comprising a reciprocatory device and an oscillatory lever, said device having an adjustable limited sliding connection with said lever for limiting the effective movement of said quick feed upon the spindle to lower the same.

10 33. In a drilling-machine, in combination, a drill-spindle; and a quick advance and return feed for said spindle, comprising an oscillatory lever having a gear connection with said spindle, said lever also having an elongated opening therein, a crank-arm, a yoke pivotally connected with said crank-arm and having a block lying within the elongated opening of said lever, adjusting-screws at each end of said elongated opening, and means for rotating said crank-arm.

15 34. In a drilling-machine, in combination, a drill-spindle having a work-feed and a quick advance and return feed, said quick feed comprising an oscillatory lever having a gear connection with said spindle, a crank-arm, a connecting-rod extending between said crank-arm and said lever, means tending to rotate said crank-arm, and means for locking said crank-arm against rotation; and means adapted to be operated by the movement of the work-feed for releasing the lock to permit the return of the spindle.

20 35. In a drilling-machine, in combination, a drill-spindle having a work-feed and a quick advance and return feed, said work-feed having a slip connection with said spindle, said quick feed comprising an oscillatory lever having a gear connection with said spindle, a crank-arm, a yoke pivotally connected with said crank-arm and having an adjustable lost-motion connection with said lever, a shaft for rotating said crank-arm, a pulley arranged to be constantly rotated mounted on said shaft and having a frictional engagement therewith, and means for locking said crank-arm from rotation; and means adapted to be operated by the movement of the work-feed for releasing said lock to permit the return of the spindle.

25 36. In a drilling-machine, in combination, a drill-spindle having a work-feed and a quick advance and return feed, said work-feed having a slip connection with said spindle, said quick feed comprising an oscillatory lever, having a gear connection with said spindle, a crank-arm, a yoke pivotally mounted on said crank-arm and having a sliding connection with said lever, means for adjustably limiting the extent of the movement of said yoke relatively to said lever, a shaft for rotating said crank-arm, a pulley on

31 said shaft arranged to be constantly rotated, means for causing said pulley to frictionally engage said shaft to rotate the shaft, and a locking-disk to prevent rotation of the crank-arm, said disk being adapted to be rotated by said shaft; and means adapted to be operated by the movement of the work-feed for releasing said locking-disk to rotation.

37. In a drilling-machine, in combination, a drill-spindle; a work-feed for said spindle; a quick advance and return feed, independent of the work-feed, for the spindle; means adapted to be actuated by the operator for starting said quick feed to advance the drill-spindle and for placing the work-feed in action; and means adapted to be automatically operated by the work-feed for actuating the quick-return feed.

38. In a drilling-machine, in combination, a drill-spindle; a work-feed for said spindle; a quick advance and return feed, independent of the work-feed, for said spindle; means adapted to be actuated by the operator for starting said quick feed to advance the drill-spindle, and for placing the work-feed in action; and means carried by said spindle adapted to start the quick-return feed when the spindle reaches a certain point in its descent.

39. In a drilling-machine, in combination, a drill-spindle; a work-feed for said spindle; a quick advance and return feed for the spindle; means adapted to be actuated by the operator for starting said quick feed to advance the drill-spindle; means adapted to be automatically operated to suspend the advancing action of the quick feed; and means adapted to be automatically operated by the work-feed for starting the quick-return feed.

40. In a drilling-machine, in combination, a drill-spindle; an oscillatory lever having a gear connection with said spindle; a crank-arm; a connecting-rod extending between the crank-arm and said lever; and means for intermittently rotating said crank-arm to oscillate said lever to quickly advance and return the drill-spindle.

41. In a drilling-machine, in combination, a drill-spindle; an oscillatory lever having a gear connection with said spindle; a crank-arm; a connecting-rod extending between the crank-arm and said lever, said connecting-rod having an adjustable lost-motion connection with said lever; and means for intermittently rotating said crank-arm to oscillate said lever to quickly advance and return the drill-spindle.

42. In a drilling-machine, in combination, a drill-spindle, a work-feed for said spindle; an oscillatory lever having a gear connection with said spindle to raise and lower the same; a crank-arm; a connecting-rod extending between the crank-arm and the lever and having an adjustable lost-motion connection with said lever; means tending to rotate said crank-arm; means for locking said crank-arm

from rotation; means adapted to be actuated by the operator for releasing said crank-arm to a partial revolution and for placing the work-feed in action; and means adapted to be automatically operated by the work-feed for further releasing said crank-arm to the remainder of its rotation.

43. In a drilling-machine, in combination, a drill-spindle having a work-feed and a quick-return feed arranged to feed said spindle alternately; means tending to drive said quick feed; a locking-disk adapted to be rotated with said quick feed, having a projecting portion for locking said disk from rotation; a rod provided with a notch adapted to receive said projecting portion; and means adapted to be operated by the work-feed for moving said rod to bring said notch into coincidence with said projecting portion to release said quick-return feed to action.

44. In a drilling-machine, in combination, a drill-spindle having a quick feed; means for driving said quick feed; a locking-disk adapted to be rotated with said quick feed, said disk having a projecting portion; a rod for locking said disk from rotation, said rod being provided with a notch adapted to receive the projecting portion of said disk; means for moving said rod to bring said notch into coincidence with said projecting portion to release said quick feed to action; and means for moving said rod to bring the notch out of coincidence with said projecting portion.

45. In a drilling-machine, in combination, a drill-spindle having a work-feed and a quick-return feed; means for driving said quick feed; a locking-disk adapted to be rotated with said quick feed, said disk having a projecting portion; a rod for locking said disk from rotation, said rod being provided with a notch adapted to receive the projecting portion of said disk; means adapted to be operated by the work-feed for moving said rod to bring said notch into coincidence with said projecting portion to release said quick-

return feed to action; and a spring-plunger for moving said rod to bring the notch out of coincidence with said projecting portion.

46. In a drilling-machine, in combination, a drill-spindle having a quick feed; means for driving said quick feed; a locking-disk adapted to be rotated with said quick feed, which disk is provided with two peripheral, concentric flanges having diametrically opposite notches between their adjacent ends; a rod for locking said disk from rotation, which rod is adapted to lie in one of the notches of said locking-disk and is provided with a notch adapted to receive one of said flanges to release said quick feed to action; and means for moving said rod to bring the notch in said rod into coincidence with one of said flanges.

47. In a drilling-machine, in combination, a drill-spindle; a shaft for rotating said spindle; a work-feed mechanism driven from said shaft and having a slip connection with said spindle; and a quick-feed mechanism for advancing said spindle driven independently of said shaft.

48. In a drilling-machine, in combination, a drill-spindle; a shaft for rotating said spindle; a work-feed mechanism driven from said shaft; a quick-feed mechanism for advancing said spindle driven independently of said shaft; and means permitting one of said feeds to overrun the other.

49. In a drilling-machine, in combination, a drill-spindle; a quick-feed shaft; means for rotating said shaft; a friction-clutch between said shaft and said rotating means; a driving connection between said shaft and said spindle for advancing said spindle; a work-feed mechanism for advancing the spindle; and means permitting one of said feed mechanisms to overrun the other.
